(57) CLAIM

The ornamental design for a food packaging with cutout window, as shown and described.

DESCRIPTION

FIG. 1 is a top view of the food packaging with cutout window showing our new design;

FIG. 2 is a front, right and top perspective view thereof; and, FIG. 3 is a front, left and top perspective view thereof. The dashed lines in the drawings indicate environment and do not form a part of the claimed design.
